UNITED STATES PATENT OFFICE.

CARRIE C. BRANDENBURG, OF WASHINGTON, DISTRICT OF COLUMBIA.

HANDKERCHIEF-DISPLAY CARD.

Application filed May 16, 1925. Serial No. 30,781.

To all whom it may concern:

Be it known that I, CARRIE C. BRANDENBURG, a citizen of the United States, residing at Washington, D. C., have invented certain new and useful Improvements in Handkerchief-Display Cards, of which the following is a specification.

My invention relates to improvements in display cards, and more particularly to a card of this character adapted to display women's handkerchiefs in a novel, ornamental and attractive manner.

The invention relates more specifically to the combination of elements which combine to produce a new and novel article of manufacture, and the method of displaying the handkerchief on the card. The method involves the formation of the card, and the folding of a handkerchief in such a manner, that the two co-operate to display the combination of colors and other means employed to ornament the handkerchief, by detachably securing the handkerchief folds to the card in a manner to produce various styles of women's frocks.

Due to its pleasing and ornamental appearance, the display device forming the subject matter of this invention, greatly enhances the sale of women's fancy handkerchiefs, for use as gifts, favors, prizes, etc. The device may also be effectively used to assist the purchaser in the selection of certain handkerchiefs to be used with certain frocks.

It will be understood that the embodiment of the device disclosed herein is restricted to the use of a single handkerchief in the production of the frock representation, the handkerchief being folded to produce the desired effect without mutilating the handkerchief in any way, or destroying its usefulness when removed from the card. Several handkerchiefs may also be employed, within certain limits, in the production of my improved display card, without departing from the spirit of my invention.

In the accompanying drawings, forming a part of this specification, and on which similar reference characters indicate similar parts, I have shown in:

Fig. 1 a front plan view of one form of handkerchief display card, made in accordance with my invention. In this figure I have shown an assembled display card which which is detachably mounted a separate card fashioned at the upper and lower extremities to represent the head and limbs of a girl, and a handkerchief folded and detachably secured to the card in a manner to display the ornamented border in the representation of a woman's frock.

Fig. 2 is a detail view illustrating the first step in the method of folding the handkerchief and securing the folds to the card to produce the lower portion of the style of frock shown in Fig. 1.

Fig. 3 is another detail view illustrating the continuance of the method disclosed in Fig. 2 in folding the remaining portions of the handkerchief, and securing the folds to the card, to produce the upper portion of the style of frock shown in Fig. 1.

Fig. 4 is a fragmentary view, illustrating the method of folding the yoke of the frock shown in Fig. 3, to display the border and edge of the handkerchief without mutilating the fabric, and,

Fig. 5 is a slightly modified form of the invention disclosed in Fig. 1, illustrating another method of utilizing the ornamented border designs in women's handkerchiefs with my improved display card in the production of various styles of frocks.

Referring now particularly to Fig. 1, I have shown a suitable ground board 1, composed of relatively stiff paper board as a backing or supporting card for the handkerchief display card 2.

In this figure, as well as in the modified form disclosed in Fig. 5, I have shown the ground board 1 of rectangular formation with a colored border 3 extending around the entire edge thereof. It will be understood however that the ground board 1 may be formed in any desired shape and from any suitable material, and ornamented as desired, without departing from the scope of the invention.

The card 2, is likewise preferably formed of a good grade of paper, such as for instance, artists' water color paper, which will permit of free hand coloring, which greatly enhances the value of articles of this character, and comprises a substantially rectangular body portion 4. The side edges of the body portion 4 as shown, are parallel to provide straight edges on which to fashion the frock hereinafter to be described. The side edges may of course be varied as desired, and, in accordance with the prevailing lines of women's frocks, as will be understood.

At the upper portion of the body portion 4 the card is shaped to represent the shoulders 5, neck 6 and head 7 of a girl, see Figs. 1 and 3. These portions which may be exposed in the completed or assembled article, as shown in Fig. 1, are finished by drawing, painting or printing the face and head dress 8, of a girl. The lower extremity of the body portion 4 is formed with depending portions 9 and 10, respectively, representing the limbs and feet of the girl. The depending portions 9 and feet 10 may be colored and ornamented as desired.

Arms 11 are also preferably formed of paper and are adapted to be pivotally attached by pins or other suitable detachable means to the rear of the card 2, as will be understood from the following.

By way of illustration I will refer first to Fig. 1, which shows a woman's fancy handkerchief 12, folded and secured by pins to the body portion 4, of the card 2. The effect is a smartly designed frock with an overskirt and blouse, which is formed by the ornamented border 13 of the handkerchief 12. In this instance we will assume for example, that the body portion of the handkerchief is formed of blue material, the border 13 white material, and the edge 14 is finished in a contrasting color to the border as shown in Fig. 2. The handkerchief 12 is placed over the card 2 and the lower portions folded in at each side behind the card and secured by pins 15. The remaining lower portions of the handkerchief are then folded over the front of the card 2, and the edges 14, of the border 13, brought into abutting relation and secured by ornamental pins 15.

In Figs. 3 and 4 I have shown the method of folding the upper portions of the handkerchief 12 in a manner to produce a blouse 16, yoke 17 and collar 18, from the white ornamented border 13, which overlies and exposes the blue underbody of the handkerchief. In each step in the operation, it will be noted that the body portion of the handkerchief 12 is utilized to produce the effect of the underdress, and the border 13 and ornamented edge 14 for overdrapes and trimming.

When the various steps in folding and securing the handkerchief to the card are completed, the arms 11 are detachably secured to the rear side of the card by pins. The figure thus produced is then detachably fastened to the ground board 1 in any desired manner.

The frocks represented by the folded handkerchief as shown in Figs. 1 and 5, may be ornamented and trimmed in accordance with the fashions in vogue. Glass beads or small paper disks, colored to represent buttons, etc., may be placed on certain of the pins used to secure the folded handkerchief to the card, or a narrow ribbon may be secured around the card and handkerchief to represent a belt as shown in Fig. 5.

I have shown the card 2 cut to represent the figure of a girl, but it will be understood that the card may be cut to conform to the figure of a woman, boy or man, and the handkerchief folded and secured to the card so as to simulate a garment appropriate for wear by the particular figure represented by the card.

What I claim is:

1. A display card comprising a ground board, a form card fashioned to represent the body, head and limbs of a girl, a handkerchief folded on the form card to represent a frock, means for detachably securing the handkerchief folds to the form card, and means for detachably securing the form card to the ground board.

2. A device of the character described comprising a card cut to conform to the outlines of the human figure, and a handkerchief secured to the card and draped therearound in simulation of a garment.

In testimony whereof I affix my signature.

CARRIE C. BRANDENBURG.
